SKIP-STITCH SEWING MACHINE

Louis Rivers, Mount Vernon, N. Y., assignor to
 American Blind Stitch Machine Company,
 New York, N. Y., a corporation of New York

Application August 22, 1935, Serial No. 37,288

5 Claims. (Cl. 112—178)

The present invention relates to improvements in the type of machines disclosed in Charles A. Dearborn Patent No. 2,000,929 granted May 14, 1935 for work supporting means for sewing machines. The mechanism of this patent was designed for producing a succession of widely spaced deep stitches with one or more shallow or skip-strokes between successive deep stitches, the result being accomplished by intermittently lowering the yieldingly mounted work-supporting frame carrying the ridge-forming member which moves in unison therewith and preferably oscillates back and forth beneath and across the path of the needle.

In this Dearborn type of blind stitch sewing machine the yieldingly mounted work-support is constructed to yield to permit its manual depression for the insertion and removal of the work between it and a stationary presser-foot, and to automatically yield to the extra downward pressure caused by the passage of an extra thickness in the work such as in crossing seams.

In the mechanism of the above-named patent the change from deep to shallow or skip-strokes is effected by an automatic mechanism that periodically lowers and raises the work-supporting frame and ridge-forming member carried thereon, —(said ridge-forming member and frame being unyielding relatively and therefore moving in unison toward and away from the presser-foot), —so that the thickness of the bight of material presented to the needle will vary according to the height of the active part of the ridge-forming member (determined by the height of the work-supporting frame) at the moment the needle penetrates the work. While this mechanism has been successful in operation it is mechanically objectionable to continually rock the work-supporting frame for lowering and raising the ridge-forming member, because of the wear and tear upon the mechanism which is under very heavy spring pressure and is normally run at very high speed, and also because of the annoying vibration of the work and the hands of the operator directing the work.

To this end the present invention has for its object the production of a machine of the general type referred to for performing skip-stitch work without the objectional periodic movement of the work-supporting frame.

In the present invention (the spring sustained work-supporting frame may still be manually lowered for the insertion and removal of work), the ridge-forming member is mounted upon an auxiliary frame which extends beneath and is

movably mounted upon the work-supporting frame; said auxiliary frame forming no part of the work-support and being itself yieldingly held in position upon the work-support by a relatively light independent spring. With this arrangement the ridge-forming member moves independently of and upon the work-supporting frame and is periodically and automatically actuated by a suitable mechanism to raise and lower it with reference to the stationary presser-foot in timed relation with the stitch-forming mechanism to produce the desired succession of spaced deep stitches and the intervening shallow or skip-strokes. The number of shallow or skip-strokes between successive deep stitches is determined by the gear ratio of the operating mechanism as in the above-named patent. With this new arrangement the independently movable ridge-forming member will also move with the work-supporting frame when it yields automatically to the pressure of an increased thickness of a seam passing between it and the presser-foot, and also when the work-supporting frame is manually depressed for the insertion and removal of work. The auxiliary frame carrying the ridge-forming member is preferably normally held by its spring in its low position upon the work-support for making blind or skip-strokes, and its operating mechanism periodically raises the auxiliary frame to high position to produce the spaced deep stitches. The light spring sustaining the auxiliary frame of the ridge-forming member yields more readily to its operating mechanism than formerly did the whole work-supporting frame with its more powerful sustaining spring. In the new arrangement less power is required and there is less wear and tear upon the machine in operating the independently movable ridge-forming member.

In order that the invention may be fully understood it will first be described with reference to the accompanying drawings and the novelty afterwards pointed out more particularly in the annexed claims.

In said drawings

Figure 1 is a plan view of the improved machine embodying the present invention, parts being broken away for the sake of clearness;

Figure 2 is a side elevation of the same;

Figure 3 is a vertical longitudinal sectional view taken on the line 3—3 of Figure 1;

Figure 4 is a detail vertical transverse sectional view taken on the section line 4—4 of Figure 3;

Figure 5 is a view similar to Figure 3 showing the parts in a slightly changed position; and

Figures 6 and 7 are detail sectional views illustrating different phases of the work performed by the improved machine.

The main frame of the machine of the type to which the present improvements are particularly applicable is formed of a single heavy casting having integral strengthening ribs and comprising essentially a rigid central base 1, centrally perforated for rigid bolting to a work bench, the upwardly extending main arm 2 at the rear terminating in the shaft bearing sleeve 3 from the left of which projects the forwardly extending arm 5 having horizontal bearings for the usual needle rock-shaft. This forward machine arm 5 also supports the looper and feed bar in the well-known manner.

Extending forwardly and upwardly from the front of base 1 is the integral arm 6 terminating in the sleeve 7 in which is secured the front horizontal bearing shaft or rod 8 upon which is pivoted the work-support 40, presently to be described.

10 is the main driving shaft of the machine journaled in the sleeve bearing 3 of the rear arm 2 and having secured at one end the combined driving pulley 11 and fly-wheel 12.

The forwardly extending needle rock-shaft journaled in the frame bearings has rigidly mounted upon its forward end the needle carrying rock-arm 16 in which is mounted the usual curved needle 17. The machine is provided with the usual thread guides and tension devices which form no part of the present invention and are therefore not referred to in detail.

18 is the operating mechanism for the needle rock-shaft is the same as in the well-known Dearborn type of blind stitch sewing machines.

40 is the work supporting frame formed with the spaced bearing sleeves 41 which are freely journaled upon the oppositely projecting ends of the rod or shaft 8 carried in sleeve 7 in the upper end of frame arm 6. These bearing sleeves 41 rest snugly against the finished vertical side faces of the sleeve 7 which they embrace. Projecting downwardly from one of the bearings 41 is an integral rock-arm 42 engaged at its lower end by a heavy coil spring 43 which extends rearwardly from said arm 42 to one arm of a stout horizontal bell crank lever 44 which is pivoted at 45 to the base 1. The other arm of bell crank 44 is engaged by an adjustable screw stop 46 threaded through the strengthening rib 1a of the base frame, the described arrangement giving to the pivoted cloth-supporting frame 40 a strong spring support to hold it in its normal horizontal working position, which is determined roughly by any suitable adjustable screw stop upon the machine frame.

The depression of the work-supporting frame for placing the work upon the frame-horn beneath the presser-foot is accomplished by the usual treadle 75 connected by a chain or wire 75a with a link 48a hooked to the rear edge of frame 40.

60 The work supporting frame 40 is extended to the left to form a work-supporting horn as is usual with this type of machine.

An auxiliary skeleton frame 50 is journaled at its ends 50a upon conical bearing screws 51 threaded through the opposite ends of the main work-supporting frame 40. This auxiliary frame has journaled in it, upon the usual conical bearing screws 55, the oscillating shaft 61 which carries the "fulling in" ridge-forming rib or disk 60 of the usual construction. The usual inde-

pendently yielding work supporting plates or platens 70 are mounted upon opposite sides of the ridge-forming disk 60, each plate 70 being pivoted upon an arm or lever pivoted upon work-supporting frame 40 and provided with a spring in the usual manner.

The auxiliary frame 50 is provided with a central depending arm 52 to which is attached the end of a light coil spring 53 extending from a lug of the main work-support 40, said auxiliary spring tending to hold the auxiliary frame and oscillatory ridge-forming member in their depressed or lowered position upon the main work-support 40. This low position is determined by engagement of a part of the operating mechanism hereinafter referred to which is so arranged that while the independent lowering of the auxiliary frame upon the work-support is limited, said auxiliary frame and ridge-forming member can move to a lower depressed position when carried down by the depression of the work-support either automatically in crossing thick parts of the work or when manually depressed for the insertion and removal of the work. This action and the operating mechanism for the periodic lowering of the ridge-forming member will be hereinafter explained.

100 is the rigidly mounted presser-foot projecting forwardly from the under face of machine arm 5 to a position above the ridge-forming disk 60 and the work-supporting platens 70. The presser-foot is formed with the usual longitudinal slot into which a ridge of the work is pressed by the disk 60 for the action of the stitch-forming mechanism.

The shaft 61 has adjustably secured to it a downwardly presented crank arm 62 to which is pivotally connected at 63, a link 64 in turn pivoted at 65 to one arm of a bell crank lever 67 pivotally mounted upon a screw bolt 68 secured to the machine frame. The other arm of the bell crank lever 67 is pivoted to the lower end of an eccentric link 69 having a yoke at its upper end encircling the eccentric 14 which is secured upon the shaft 10 alongside of the pulley 11.

45 It will be observed that the work-supporting frame 40 projects rearwardly from the machine arm 6.

By the eccentric link connection between the power shaft 10 and the shaft 61 of the ridge-forming disk it will be observed that the forward stroke of the disk is effected by an upward thrust upon the rock-arm 62.

50 The looper mechanism of the machine is not involved in the present improvement and is not specifically shown, but it will be understood that the same form of looper is employed as has been used in the past in this Dearborn type of machine, the looper being indicated at 76 carried on the forward end of the looper rod 77 carrying on its rear end a yoke pivoted upon a sleeve which is freely journaled upon the crank-pin mounted in the angularly offset arm of the crank disk in the usual manner. This looper and its operating mechanism will be clearly understood from Dearborn Patent No. 1,467,570 dated September 11, 1923.

55 The feed mechanism may be of the general type shown in Dearborn Patent No. 815,026 dated March 6, 1906, the specific structure of the same being immaterial to the present invention.

125 is the longitudinally movable rocking feed-bar actuated at its rear end by the usual eccentric (not shown) upon main shaft 10.

70 The arm 42 of the work-supporting frame 40

engages an adjustable stop plate 42a pivotally mounted upon a bracket of machine arm 6 and held in place by an adjustable tappet screw 48 threaded through arm 6 and carrying upon its outer end a milled head 49, see Figures 1 and 5. This part of the structure is the same as shown in Dearborn Patent No. 1,964,381, dated June 26, 1934.

The lower end of an arm 54 projecting from auxiliary frame 50 engages the vertical tappet member 101a adjustably mounted on the short arm 101 of the work-controlling bell crank lever which is pivoted upon a set screw 102 threaded into a vertical face of the base frame rib 1a. The other or long arm 103 of said bell crank projects rearwardly from its pivot 102 and is formed in its rear end with a horizontal elongated slot 104 through which projects a bolt 105. A short rock-shaft 106 extends transversely of the machine below and parallel with the main shaft 10. This rock-shaft 106 is freely journaled in a suitable bearing 107 formed in the frame arm 2 just above the frame base 1. The inner end of said rock-shaft 106 carries a forwardly projecting 25 rock-arm 108 which overlaps the rear end of arm 103. The forward end of rock-arm 108 has an elongated slot 109 in which engages the end of the bolt 105 which forms a jointed connection between parts 103 and 108. The bolt 105 is formed with an enlarged head adjacent to the bell crank arm 103 upon which is freely journaled a hand-operated cam lever 110. This mechanism is the same as set forth in the above-named Patent No. 2,000,929.

35 The hand lever 110 is formed with a cam peripheral surface, designed to operate upon the upper face of the base frame 1 to shift the position of the interengaging arms 103 and 108 into inactive position and lock them in that position.

40 The rock-shaft 106 carries at its outer end an arm 115 having an anti-friction roller 116 which operates in peripheral engagement with a controlling cam 117 mounted upon and rotating with a gear 118 freely journaled upon a stub shaft 45 119 carried in the machine arm 2 beneath the main shaft 10. This gear 118 meshes with and is driven by a smaller gear 120 keyed to the shaft 10 alongside of the eccentric link 69. The intermeshing gears 118 and 120 may have any 50 desired ratio such as 2:1, 3:1, etc., depending upon the number of impulses it is desired to impart to the system of levers which control the periodic movement of the auxiliary frame carrying the ridge-forming member upon the work-support.

55 It will be observed that the engagement of anti-friction roller 116 of lever 115 with the high portion of cam 117 rocks the long arm 103 of the work controlling bell crank to press upon the tappet arm 54 and slightly raise the ridge-forming member 60 by which the work is supported in the path of the needle. This position of the parts is illustrated in Figures 5 and 7, the needle in the stitching operation taking a deep bite in the work 65 which, when operating upon a hem, will pass through the edge of the hem and the lower layer or base material. When the roller of rock-arm 115 is in engagement with the low portion of cam 117 the work support is in position to present 70 the ridge-forming member 60 in a slightly lower elevation as shown in Figures 3 and 6, in which position the needle passes through a shallower bite of the material passing through the edge of the turned over layers and skipping the base material or making a blind stitch therein.

In Figures 3 and 6 of the drawings the ridge-forming member 60 is shown in its lowest position at the moment of penetration of the needle 17, the view showing the needle passing through the upper two layers of material *a* and *b* and missing the lower layer or base material *c*. In this position the mechanism is performing what is referred to as the skip-stitch. In Figures 5 and 7 the ridge-forming member 60 is shown in its elevated position in which a bigger bite or ridge 10 is formed in the work. In this position of the parts the needle 17 is represented as penetrating all three layers of the work, making a deep stitch. In the form of machine illustrated the ratio of 15 the gears is such that two of the skip-strokes are formed between two adjacent deep stitches.

The spring 53 normally holds the auxiliary frame and ridge-forming disk 60 in low position upon the work-support. This low position is determined by the engagement of arm 54 with 20 tappet arm 101a. By adjusting the position of this arm 101a upon the short arm 101 of the operating bell crank lever the exact low position of the auxiliary frame can be determined. While the engagement of arms 54 and 101a normally limits 25 the low position of the auxiliary frame upon the work support it will be clear that said arms do not interfere with the free downward depression of the work-support for inserting or removing work and to automatically take care of the passing of extra thickness like seams in the work.

The tappet arm 101a may be adjustably mounted upon the arm 101 of the bell crank by any suitable means. As shown in the drawings 35 this arm 101a is formed with a box-like housing embracing the arm 101 and pivotally mounted thereon by a machine screw 101b. An adjusting screw 101c is threaded through one of the walls of the tappet arm housing and engages the arm 101 for accurately locating the tappet arm 101a 40 with reference to the arm 54 of the auxiliary frame.

I claim:—

1. The combination, in a sewing machine, with a presser-foot, a driving shaft, a work-support beneath said presser-foot, and suitable work-feeding and stitch-forming mechanisms, of a uniformly oscillating ridge-forming member mounted for independent oscillation and bodily movement upon said work-support, and timed operating mechanisms actuated by said shaft for periodically oscillating and bodily raising and lowering the ridge-forming member upon and independently of said work-support in timed relation to said stitch-forming mechanism, whereby successive deep stitches and intervening shallow skip-strokes are formed.

2. The combination, in a sewing machine, with a fixed presser-foot, a driving shaft, a yielding work-support beneath said presser-foot, and suitable work-feeding and stitch-forming mechanisms, of an auxiliary frame movably mounted upon said work-support, a ridge-forming member mounted upon said auxiliary frame and uniformly 60 movable thereon, and timed operating mechanism between said shaft and said auxiliary frame for periodically moving said frame for bodily raising and lowering said ridge-forming member with relation to said presser-foot.

3. The combination, in a sewing machine, with a fixed presser-foot, a driving shaft, a yielding work-support beneath said presser-foot, and suitable work-feeding and stitch-forming mechanisms, of an auxiliary frame movably mounted 65

upon said work-support, a uniformly oscillating ridge-forming member mounted upon said auxiliary frame and movable bodily therewith independently of said work-support, and timed operating mechanisms between said shaft and said ridge-forming member and said auxiliary frame respectively for periodically oscillating and bodily raising and lowering the ridge-forming member with relation to said presser-foot.

10 4. The combination, in a sewing machine, with a fixed presser-foot, a driving shaft, a yielding spring supported work-support beneath said presser-foot, and suitable work-feeding and stitch-forming mechanisms, of an auxiliary spring supported frame movably mounted upon said work-support, a ridge-forming member mounted upon said auxiliary frame and movable bodily therewith independently of said work-support, the spring supporting said auxiliary frame being relatively more yielding than the spring supporting said work-support, and timed

operating mechanism between said shaft and said auxiliary frame for periodically bodily raising and lowering the ridge-forming member with relation to said presser-foot.

5 5. The combination, in a sewing machine, with a fixed presser-foot, a driving shaft, a yielding work-support beneath said presser-foot, and suitable work-feeding and stitch-forming mechanisms, of an auxiliary frame movably mounted upon said work-support, a uniformly oscillating ridge-forming member mounted upon said auxiliary frame and movable bodily therewith independently of said work-support, independent sustaining springs for said work-support and said auxiliary frame, and timed operating mechanisms 10 between said shaft and said ridge-forming member and said auxiliary frame respectively for periodically oscillating and bodily raising and lowering the ridge-forming member with relation to said presser-foot.

15 LOUIS RIVERS.
